US0D1100925S

(12) **United States Design Patent** (10) Patent No.: **US D1,100,925 S**
(45) Date of Patent: ** Nov. 4, 2025

(54) **ELECTRONIC DEVICE WITH GRAPHICAL USER INTERFACE**

- (71) Applicant: **Apple Inc.**, Cupertino, CA (US)
- (72) Inventors: **Kevin Will Chen**, Cupertino, CA (US); **Taylor Gerard Carrigan**, San Francisco, CA (US); **Charmian Naguit**, San Francisco, CA (US)
- (73) Assignee: **Apple inc.**, Cupertino, CA (US)
- (**) Term: **15 Years**
- (21) Appl. No.: **29/915,255**
- (22) Filed: **Oct. 27, 2023**

Related U.S. Application Data

- (63) Continuation of application No. 29/782,897, filed on May 10, 2021, now Pat. No. Des. 1,003,309, which is a continuation of application No. 29/757,003, filed on Nov. 2, 2020, now Pat. No. Des. 918,945, which is a continuation of application No. 29/662,861, filed on Sep. 10, 2018, now Pat. No. Des. 900,830.

CLAIM

The ornamental design for an electronic device with graphical user interface as shown and described.

DESCRIPTION

The FIGURE is a front view of an electronic device with graphical user interface showing the claimed design. The outer dashed broken lines in the figure show a display screen, or an alternate electronic device having a display screen, and form no part of the claimed design. The other dashed broken lines in the figure show portions of the graphical user interface that form no part of the claimed design.

1 Claim, 1 Drawing Sheet
